UNITED STATES PATENT OFFICE.

JEANNE L. DRUCKLIEB, OF NEW YORK, N. Y.

DESIGN FOR A SHAKER FOR SALT AND PEPPER OR SIMILAR ARTICLE OF MANUFACTURE.

Application filed March 31, 1928. Serial No. 26,081. Term of patent 7 years.

To all whom it may concern:

Be it known that I, JEANNE L. DRUCKLIEB, a citizen of the United States, residing in the city of New York, county of Bronx, and State of New York, have invented a new, original, and ornamental Design for a Shaker for Salt and Pepper or Similar Article of Manufacture, of which the following is a specification, reference being had to the accompanying drawing, forming a part thereof.

Fig. 1 is a front view and Fig. 2 is a rear view of a shaker embodying my design.

I claim:

The ornamental design for a shaker for salt and pepper or similar article of manufacture, substantially as shown.

JEANNE L. DRUCKLIEB.
